UNITED STATES PATENT OFFICE.

JAMES LEEROY CATES, OF SENATOBIA, MISSISSIPPI.

DESIGN FOR A WIRE-STRETCHING TOOL.

SPECIFICATION forming part of Design No. 28,105, dated December 28, 1897.

Application filed September 18, 1897. Serial No. 652,195. Term of patent 14 years.

To all whom it may concern:

Be it known that I, JAMES LEEROY CATES, a citizen of the United States, residing at Senatobia, in the county of Tate and State of Mississippi, have invented and produced a new and original Design for a Wire-Stretching Tool, of which the following is a specification, reference being had to the accompanying drawings, forming a part thereof, in which—
5 Figure 1 is a side elevation of a wire-stretching tool embodying the features of my design, and Fig. 2 is an edge view of the same.
10 The leading feature of the design consists in the straight-handle section A, terminating at its lower end in the fork B, a yoke-body C,

curved from the handle, a straight arm D, extending from the terminal of the yoke, and a claw E, projected from the arm over the convexed edge of the yoke.

A minor feature of the design consists in a 20 shoulder *a* where the arm D connects with the claw E.

I claim—

The design for a wire-stretching tool herein shown and described.

JAMES LEEROY CATES.
